Thomas S. Lo Duca and Guy S. Lo Duca,
Milwaukee, Wis.

Application February 13, 1953, Serial No. 23,608

Term of patent 14 years

(Cl. D86—9)

To all whom it may concern:

Be it known that we, Thomas S. Lo Duca, a citizen of the United States, residing at Milwaukee, in the county of Milwaukee and State of Wisconsin, and Guy S. Lo Duca, a citizen of the United States, residing at Milwaukee, in the county of Milwaukee and State of Wisconsin, have invented a new, original, and ornamental Design for a Jewel Case, of which the following is a specification, reference being had to the accompanying drawing, forming a part thereof.

In the drawing:

Fig. 1 is a top plan view of a jewel case showing our new design;

Fig. 2 is a transverse sectional view thereof showing the case in open position;

Fig. 3 is a front elevation thereof;

Fig. 4 is an end view thereof; and
Fig. 5 is a rear elevational view of the case.
We claim:

The ornamental design for a jewel case, as shown.
